US0D1042944S

(12) **United States Design Patent** (10) Patent No.: **US D1,042,944 S**
(45) Date of Patent: ** Sep. 17, 2024

(54) **LIGHTING FIXTURE**

(71) Applicant: **HLI Solutions, Inc.**, Greenville, SC (US)

(72) Inventors: **Perry Romano**, Bradenton, FL (US); **Adam J. Clark**, Bradenton, FL (US); **Michael D. Toth**, Miami Beach, FL (US)

(73) Assignee: **HLI Solutions, Inc.**, Greenville, SC (US)

(**) Term: **15 Years**

(21) Appl. No.: **29/709,671**

(22) Filed: **Oct. 16, 2019**

Related U.S. Application Data

(63) Continuation of application No. 29/602,985, filed on May 5, 2017, now Pat. No. Des. 864,466.

(57) **CLAIM**

The ornamental design for a lighting fixture, as shown and described.

DESCRIPTION

FIG. 1 is a perspective view of a lighting fixture according to the design;

FIG. 2 is a side, elevation view of the lighting fixture of FIG. 1;

FIG. 3 is another side, elevation view of the lighting fixture of FIG. 1;

FIG. 4 is a front, elevation view of the lighting fixture of FIG. 1;

FIG. 5 is a rear, elevation view of the lighting fixture of FIG. 1;

FIG. 6 is a top, plan view of the lighting fixture of FIG. 1; and,

FIG. 7 is a bottom, plan view of the lighting fixture of FIG. 1.

The broken lines in the drawings illustrate portions of the lighting fixture which form no part of the claimed design.

1 Claim, 7 Drawing Sheets
